(57) **CLAIM**

The ornamental design for a folding chair as shown and described.

DESCRIPTION

FIG. 1 is a perspective view of a folding chair showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1, which shows the rhombus checkered design of the chair seat;

FIG. 10 is an enlarged view of area 10 shown in FIG. 1, which shows the armrest of the chair;

FIG. 11 is an enlarged view of area 11 shown in FIG. 2, which shows a cup holder design at the armrest of the chair;

FIG. 12 is an enlarged view of area 12 shown in FIG. 2,

which shows the magazine pocket design on the right side of the chair seat;

FIG. 13 is an enlarged view of area 13 shown in FIG. 2, which shows the bottom of one of the chair feet; and,

FIG. 14 is a rear perspective view thereof, shown with the

retractable cords on the back of the chair in a second position of use.

The evenly-spaced broken lines show portions of the folding chair that form no part of the claimed design; the dash-dot-dash broken lines indicate the cutoff boundaries for enlarged detail portion views and form no part of the claim.

1 Claim, 14 Drawing Sheets
